ENVELOPE CONSTRUCTION

Robert H. Hemphill, Miami Beach, Fla.

Application July 1, 1936, Serial No. 88,473

7 Claims. (Cl. 229—86)

This invention relates to envelopes of that type wherein an opener in the form of a thread, cord or fine wire is placed along and inside of an edge of the envelope so that the latter may be opened simply by exerting a quick pull on the thread and slitting the edge.

Envelopes having opening means of this type are convenient and there is a wide demand for the same in the market, but despite the numerous attempts as evidenced by the prior art to produce a marketable or commercially practicable job no one has apparently heretofore been successful. The problem is not as simple as would appear at first glance. Envelopes must be produced at a very low cost, and the incorporation of the opening member should not require added manual labor, complex machinery or retard the manufacturing operation. The envelope should meet the requirements of the postal authorities. There should be no projecting parts at the corner or elsewhere to catch and tear nor should there be any unsightly thickened or bulky portions which would be crushed and mutilated by the stamping machine, or scoring or perforations to weaken the envelope. The edge-cutting thread must be relatively fine and this renders it exceedingly difficult to handle by automatic machinery. If adhesive is applied to that portion of the thread which is exposed to the contents of the envelope, it will adhere to the contents and may mutilate the latter during the opening operation. The thread must be located in such position that it will not be caught by, or interfere with the contents of the envelope while the latter is being loaded and sealed.

I have devised an improved self-opening envelope and method of making same which effectively meets and overcomes the foregoing problems. In my method the arrangement is such that the thread may be drawn in a straight line across and at right angles to the path of travel of the envelope blank and held relatively taut while being severed and positioned, and no manual handling of the thread is required to position same in the envelope. The thread preferably extends along the bottom edge of the envelope and there is no glue or adhesive on its exposed portion to adhere to the contents of the envelope. The incorporation of the thread adds no material cost to the production of the envelopes. The completed envelope has no weakened portions at the corners or elsewhere, there are no projections or thickened portions, and in fact the envelope is substantially similar in every way to the ordinary envelope except that

I prefer to use an indicating mark for the tearing portion.

The various features of novelty and advantage of my improved envelope and method of manufacture will become more apparent in view of the following description taken in conjunction with the drawing, wherein.

Fig. 1 is a view in plan of an envelope blank preparatory to receiving the thread;

Fig. 2 shows the thread length cut and in place 10 in the blank;

Fig. 3 shows the succeeding folding operation;

Fig. 4 shows the completed envelope.

A blank is first cut substantially as shown in Fig. 1 with a body 5, opposed side or end flaps 15 6 and 6a, a bottom flap 7 and sealing flap 8.

Preferably simultaneously with the blank-cutting operation, tabs or ears 9 and 9a are formed at the opposite edges of the blank at the junction of the bottom flap 7 with the side or end flaps 6 and 6a. These tabs or ears are preferably formed on the flaps 6 and 6a by the blank-cutting die, not shown in the drawing but construction of which is well understood in the art.

An adhesive may then be applied along the 25 marginal edges of the bottom flap 7 and to the tabs 9 and 9a.

A thread 10 is stretched over the path of travel of the blank, and as the folding line 11 registers with the thread, the tabs 9 are folded 30 over the thread against the surfaces of the flaps 6 and 6a and sealed, catching and holding the thread ends. The thread may be severed before, after or during its positioning in the blank, depending upon the design of the thread handling mechanism. In one design, the thread is gripped at spaced points, severed and then lowered into registration with the line 11 and tabs 9, the tabs then folded and the thread length released, while in another design the thread is severed after the 40 tabs are folded. In any event, the fact that the ends of the thread require no curling, knotting or folding materially simplifies the automatic placement of the thread lengths.

The next step is shown in Fig. 3, the flaps 6 45 and 6a being folded over carrying the tabs 9 and 9a and thread ends therewith turning the thread ends back re-entrantly and securely holding the same in place. It will be noted that no surface having glue or adhesive thereon is exposed to 50 the interior of the envelope. Another important feature is that the folding back of the flaps 6 and 6a with the tabs thereon in effect locks the thread ends in place so that the adhesive is not solely depended on for this function, and this 55

locking action follows in the normal manufacture of the envelope.

Finally, the bottom flap 7 is folded over and sealed against the flaps 6 and 6a and after drying of the adhesive, the sealing flap is folded over as shown in Fig. 4. It is preferred to make indicating marks 12 at opposite lower corners of the envelope to indicate the portions to be torn off the envelope when it is desired to open the same, and to also show that the envelope is of the self-opening type. Any suitable mark may be adopted or this feature may be omitted if desired.

The handling of the thread and folding of the tabs 9 and 9a may be done by automatic machinery, and while I have not shown any preferred type of mechanism for accomplishing this purpose, yet it will be understood that suitable mechanism may be adopted by those skilled in the art. Since the thread is placed along the bottom edge of the envelope, it will be out of the way of the contents of the same when inserted in the envelope. There are no glued surfaces exposed to the contents of the envelope either on the thread or the tabs for holding the thread. The strength of the envelope remains unimpaired since there are no apertures or weakened surfaces caused by perforations or scoring. Further there are no bulges such as would be formed by knots nor are there any projecting ears or tabs at the corners which would catch and tear during handling in the mails. I have found that this type of self-opening arrangement may be embodied in the usual envelope making machinery simply by the addition of mechanical thread positioning and severing mechanism and tab folding mechanism of relatively simple construction.

The opening operation is simple and well understood, it being only necessary to tear off one of the bottom corners of the envelope and give the thread a relatively sharp pull at approximately a right angle to the bottom edge of the envelope.

It will be understood that certain minor changes in the steps of the method and in the structure and arrangement of the thread-holding tabs may be adopted within the scope of the invention as defined by the appended claims.

I claim:

1. In the manufacture of envelopes, the step which consists in forming thread-holding tabs in the marginal edge of an envelope blank at the opposite ends of the line of fold of a folding flap, holding a thread free of adhesive over, and in substantial registration with said line of fold and said tabs and folding the latter over to hold the thread, and thereafter folding the tabs and thread ends back over the body of the blank.

2. The method of making an envelope of that type having an opening thread underlying an edge thereof, which consists in first forming a blank with a body portion and opposed side and bottom folding flaps and thread-retaining tabs or ears in the marginal edges of the blank at the juncture of the side flaps with the bottom flap, holding a thread length in a non-slack condition over the line of fold of the bottom flap and folding the tabs over the thread and securing them against the end flaps, then folding the end flaps and tabs over the body and finally fold-

ing the bottom flap over and securing it to the end flaps.

3. The method of making an envelope of that type having an opening thread underlying an edge thereof, which consists in first forming a blank with a body portion and opposed side and bottom folding flaps and simultaneously forming thread-retaining tabs or ears in the marginal edges of the blank at the juncture of the end flaps with the bottom flap, applying an adhesive to the marginal edge of the bottom flap and also to the tabs, holding a thread length relatively taut over the line of fold of the bottom flap and folding the tabs over the thread and against the end flaps, then folding the end flaps and tabs over the body and finally folding the bottom flap over and securing it to the end flaps.

4. The method of making an envelope of that type having an opening thread underlying an edge thereof, which consists in first forming a blank with a body portion and opposed side and bottom folding flaps with thread-retaining tabs or ears on the side flaps adjacent the opposite ends of the line of fold of the bottom flap, applying an adhesive to said bottom flap and also to the tabs on each end flap and holding a thread length relatively taut over and in substantial registration with the said line of fold and tabs or ears and folding the tabs or ears over against and securing them to the inner surfaces of the side flaps, then folding the side flaps over the body portion and finally folding the bottom flap over and securing it to the end flaps.

5. An envelope having a body portion with folding flaps at opposite sides thereof and a bottom folding flap, thread-retaining tabs at opposite ends of the line of fold of the bottom flap folded over and secured to the inner surfaces of said side flaps, and an edge-slitting thread extended along said line of fold with its opposite ends caught by said tabs and turned inwardly due to the folding of the side flaps, the thread length between its caught ends being free of adhesive material.

6. An envelope having side and bottom folding flaps and an edge-slitting thread lying within the bottom edge thereof with its opposite ends caught by tabs which are formed on the side flaps and turned inwardly and secured to the inner surface of the latter, said thread being free of adhesive between its caught ends and the corners of the envelope being unweakened and free of projections.

7. An envelope having a body portion and a pair of oppositely disposed flaps which are folded inwardly over the body portion, another flap folded at substantially a right angle to the first-named flaps and overlapping and secured to said first-named flaps, an edge-slitting thread extending along the line of fold of the overlapping flap, thread holding tabs or ears located adjacent the ends of the line of fold of the overlapping flap and turned inwardly over the opposite ends of the thread against the inner surfaces of the oppositely disposed flaps, said thread ends and tabs being turned inwardly over the body portion and the thread ends substantially locked in position due to the folding of the oppositely disposed flaps.
